UNITED STATES PATENT OFFICE

ROBERT HUDSON WAGER, OF JERSEY CITY, NEW JERSEY

LATHER-FORMING DEVICE

Application filed January 5, 1928. Serial No. 244,732.

The invention relates to new and useful improvements in lather forming devices for shaving purposes, of the same general type disclosed in my U. S. Patents 1,554,146; 1,554,147 and 1,554,148 all of Sept. 15, 1925, and in my pending U. S. application Serial No. 174,320.

A great many users of lather forming devices such as those above referred to, often 10 rest the device upon a radiator or other warm support, to heat the contained liquid for the purpose of obtaining a warm lather, and through inadvertence, the devices are often left upon the radiator or the like after they 15 have been used. The result is that the soap cake will become more or less dissolved in the liquid and the thick pasty soap thus formed, will settle to the bottom of the liquid containing chamber, at which point it clogs 20 the inlets through which air under pressure or other gas is forced into the liquid and soap containing chamber for the purpose of generating bubbles, which bubbles are later 25 condensed and converted into thick creamy lather.

It is one object of the present invention to provide new and improved means whereby any accumulated soap in the lower portion 30 of the liquid container, may be readily loosened to again expose the gas inlets so that the device may be readily used.

Lather forming devices of the general type to which I have above referred, embody a cap at the upper end of the device, capable of 35 being manually turned, and it is a further aim of the invention to provide a construction in which turning of this cap will actuate the soap loosening means. In this connection, a still further aim is to provide a construction 40 in which the bubble condensing or converting unit acts as an intermediate driving member between the cap and the soap loosening means.

Yet another aim is to provide a construction which, while being rather simple and inexpensive, will be efficient, reliable and in every way desirable.

With the foregoing in view, the invention resides in the novel subject matter herein- 45 after described and claimed, the description

being made with reference to the accompanying drawing.

Figure 1 is a vertical sectional view partly in elevation, showing a lather forming device improved in accordance with the present invention. 55

Fig. 2 is a horizontal sectional view on line 2—2 of Fig. 1.

Fig. 3 is a perspective view showing the soap loosening device, and the bubble converting unit in juxtaposition. 60

In the drawing above briefly described, the numeral 4 denotes a container adapted to receive a quantity of water or other desired liquid. At the central portion of this container, is a post structure 5 at whose lower portion, a soap cake support 6 is provided. Gas outlet ducts 7 are located under the support 6 and are open at the peripheral edge of the latter, which edge is spaced from the peripheral wall of the container 4. The container bottom and the post structure 5 are formed with suitable gas conducting passages 8—9—10—11, for conducting gas (preferably air) to the ducts 7, from a suitable source such as a hand bulb 12. The injection of this gas into the liquid, into which the soap cake 13 extends, serves to form soap bubbles. Under the influence of the pressure within the bubble forming portion of the container 4, 70 the bubbles are extruded through a cylindrical bubble condensing unit 14 which converts them into a thick creamy shaving lather. This condensing unit 14 is rotatably received in the upper portion of the container 4 and fitting over the upper portion of said unit, is a cap 15 having a lather discharge spout 16, said cap being connected with the body of the container by a suitable lock ring 17 which when loosened permits turning of 75 the cap 15 to dispose the spout 16 in any desired direction. 85

The features of construction so far disclosed constitute no parts of the present invention except in their relation with the new 90 features of construction now to be described.

18 denotes soap loosening means disposed in the container 4, said means preferably comprising a split ring 19 contacting with the peripheral wall of the container, and arms 100

20 projecting downwardly from said ring, the lower ends of said arms being provided with ears or other desired formations such as 21, received between the peripheral wall of the 5 container 4 and the peripheral edge of the support 6. Preferably, the parts 19—20—21 are stamped from a single piece of sheet metal, and the arms may be so stamped as to provide them with longitudinal ridges 22 for 10 stiffening purposes. If desired, the ends of the split ring 19 may have an interlocking engagement to prevent such ends from shifting up and down when the soap loosening or cutting means is rotated. As shown in Fig. 3, 15 one end of the ring may have a notch 19^a to receive a tongue 19^b formed by reducing the other end, or any other suitable means may be employed to keep the ends of the ring in alinement.

20 An operative connection is provided between the soap loosening means or device 18 and the bubble condensing or converting unit 14, so that upon turning of the latter, the means 18 will be operated to loosen any accumulated soap between the peripheral edge of the support 6 and the peripheral wall of the 25 container 4. I also provide an operative connection between the cap 15 and the unit 14, so that by turning said cap manually upon 30 loosening of the ring 17, said unit 14 may be similarly turned. Hence, it will be seen that unit 14 forms an intermediate driving connection between the cap 15 and the soap loosening means or device 18, so that by 35 merely turning said cap, the lower ends of the arms 20 will plow through any accumulated soap at the peripheral edge of the support 6, thus so loosening it as to permit free discharge of gas into the container from the 40 ducts 7.

The operative connection between the soap loosening means or device 18 and the bubble condensing or converting unit 14, preferably consists of co-operable circumferentially spaced lugs 23—24 on the upper edge of the ring 19 and the lower corner of the unit 14. Similarly, the operative connection between the unit 14 and the cap 15, preferably consists of co-operable circumferentially spaced lugs 25—26.

50 While the present illustrated embodiment of the invention is especially adapted for forming lather for shaving purposes, it will be understood that my invention may be embodied in larger devices or machines for making lather for purposes other than shaving, and when this is done, the soap loosening or cutting feature would be more essential than in the smaller devices of my patents 55 above mentioned.

60 Excellent results are obtainable from the construction shown and described and hence it may be considered as preferred. However, within the scope of the invention as

claimed, numerous variations may be made.

I claim:

1. In combination with a lather forming device embodying a container for saponaceous liquid, and a removable cover swiveled upon the upper end of the container wall and capable of manual turning; means in said container for loosening accumulated soap, said loosening means being operatively connected with said cover for actuation by turning of the latter. 70

2. In combination with a lather forming device embodying a container for a saponaceous liquid, and a removable cover swiveled upon the upper end of the container wall, said cover having a lather discharge spout usable as a handle for turning said cover; means in said container for loosening accumulated soap, said means being operatively connected with said cover for actuation by 80 turning of the latter. 85

3. In combination with a lather forming device embodying a bubble generating and extruding chamber to contain a saponaceous liquid, and a bubble converting unit at the upper end of said chamber capable of manual turning; means in said chamber for loosening accumulated soap, said means being operatively connected with said bubble converting unit for actuation by turning thereof. 90

4. In combination with a lather forming device embodying a container for a saponaceous liquid, a gas inlet into said container below the liquid level, and a bubble converting unit at the upper end of said container capable of manual turning; means in said container for clearing away accumulated soap from said gas inlet, said means being operatively connected with said bubble converting unit to be actuated by turning thereof. 100

5. In a lather forming device embodying a bubble generating and extruding chamber, a bubble converting unit at the upper end of said chamber, and a cap for said upper end of said chamber capable of manual turning; connecting means between said cap and unit whereby the latter may be turned by turning of said cap, and means in said chamber for loosening accumulated soap, said means being operatively connected with said bubble converting unit to be actuated by turning thereof. 110

6. A structure as specified in claim 3; the operative connection between said soap loosening means and said bubble converting unit consisting of co-operable circumferentially spaced lugs thereon. 120

7. A structure as specified in claim 5, the operative connection between said cap and said bubble converting unit consisting of co-operable circumferentially spaced lugs thereon. 125

8. A structure as specified in claim 5; the operative connections between said bubble condensing unit, said cap and said soap loos- 130

ening means consisting of cooperable circumferentially spaced lugs thereon.

9. In combination with a lather forming device embodying a liquid container, a soap cake support therein spaced from the peripheral wall thereof and a gas inlet under said support opening at the peripheral edge thereof; a loosening device for accumulated soap mounted in said container and having a soap loosening portion operable between said peripheral wall and said peripheral edge.

10. A structure as specified in claim 9; said loosening device embodying a ring slidably contacting with said peripheral wall and an arm projecting downwardly from said ring, said arm constituting said soap loosening portion.

11. In combination with a lather forming device embodying a liquid container, a soap cake support therein spaced from the peripheral wall thereof, a gas inlet under said support open at the peripheral edge thereof, a bubble converting unit rotatably supported at the upper end of said container, and a cap for the container disposed over said unit and capable of manual rotation; a ring at the inner side of said peripheral wall under said unit and having a soap loosening portion between said wall and said peripheral edge of said support, and means operatively connecting said ring and said unit, and said unit and said cap whereby turning of the cap will turn said unit and said ring.

12. A structure as specified in claim 11; said connecting means consisting of co-operable circumferentially spaced lugs on the cap, unit and ring.

13. A soap loosener for a lather forming device, comprising a ring to engage a container wall, said ring having means for co-action with an extraneous member to provide means for turning the ring, and a soap loosening arm projecting downwardly from said ring.

14. A soap loosener for a lather forming device, comprising a ring to engage a container wall, and a soap loosening arm projecting downwardly from said ring, the latter having a lug to abut an extraneous member by which the ring may be turned.

15. A soap loosener for a lather forming device comprising a split ring to engage a container wall, the ends of the ring having an interlocking means, and a soap loosening member projecting from said ring.

55 In testimony whereof I have hereunto affixed my signature.

ROBERT HUDSON WAGER.
